UNITED STATES PATENT OFFICE.

ROBERT WACHENHEIM, OF NEW YORK, N. Y.

KEY-CHAIN.

1,048,011.

Specification of Letters Patent.

Patented Dec. 24, 1912.

Application filed June 14, 1911. Serial No. 633,087.

To all whom it may concern:

Be it known that I, ROBERT WACHENHEIM, a citizen of the United States, and a resident of New York, borough of Manhattan, in the county of New York and State of New York, have made and invented certain new and useful Improvements in Key-Chains, of which the following is a specification.

10 My invention relates to an improvement in key-chains, such, for instance, as are employed for attachment at one end thereof to some part or portion of the clothing of the wearer, the opposite end having secured thereto a ring on which the keys are suspended, in order to permit the latter to be inserted and retained within the pocket of the clothing.

It has heretofore been the custom to secure 20 to one end of the chain a "button loop" adapted to slip over one of the suspender buttons secured to the waist-band of a pair of trousers, one end of the suspender being then attached to the button, whereby the 25 chain is securely fastened to the trousers and all danger of the same becoming accidentally disengaged therefrom avoided. As is well-known, it is now the custom at certain periods of the year, particularly during 30 the summer season, to substitute for the suspenders a belt, with which to support the trousers, the suspender buttons being omitted from the waist-band or attached to the inner side or surface thereof. In order, 35 therefore, to securely fasten the chain to the clothing in such instance, it has been attempted to encircle the belt, and sometimes the suspender end, with a part of the chain, and in some way securely fasten the latter thereto; but such has proved to be incon- 40 venient as well as unsafe and unsightly, and to overcome these objections I have devised means whereby the chain may be neatly and securely fastened in place, either to a sus- 45 pender button or to the belt, as may be desired or rendered necessary.

With this and other ends in view, the invention consists in certain novel features of construction as will be hereinafter fully 50 described and pointed out in the claim.

In the accompanying drawings, Figure 1 is a view in elevation of a key-chain constructed in accordance with my invention, a portion of a belt being shown in dotted lines. 55 Fig. 2 shows the chain reversed and suspended from a button attached to the waist-

band of a pair of trousers, the button and portion of the waist-band being shown in dotted lines.

Referring to the drawings, 5 represents a 60 chain, of any desired kind, type or style, and of any suitable length, and such as is usually employed in the manufacture of articles of this kind. To one end of the chain is secured a fastener 6, termed by me a 65 "belt loop," preferably formed of a single continuous piece of wire, this loop being of sufficient length and breadth as to nicely contain a belt 7, such as is usually worn around the waist to support a pair of trousers in lieu of suspenders. On the opposite end of the chain is secured what is generally known and referred to by the trade and public as a "button loop" 8, also preferably 70 formed of wire and of the shape such as that 75 of the button loops commonly provided on the ends of the straps of overalls and other like garments, this loop being adapted to fit over a suspender button. In those instances where no suspender buttons are provided on the waist-band of the trousers, and a belt 7 worn as a substitute for the suspenders to support the trousers, the chain is 80 suspended as illustrated in Fig. 1, that is, the belt 7 is passed through the loop 6, the 85 key-ring 9, with its attached keys 10, being hung on the button loop 8; when, however, trousers are worn provided on the waist-band with buttons 11, sewed or otherwise attached to the waist-band 12, as illustrated 90 in Fig. 2, and to which buttons suspenders are to be attached, the chain is reversed, the key-ring 9, with its attached keys 10, being engaged with the belt loop 6, the button loop 8 being passed over and engaged with 95 the button 11.

From the foregoing it will be understood that the key-chain so constructed and arranged may be worn and conveniently and securely attached either to the belt or to a 100 suspender button, it being necessary only to reverse the chain end for end, and the key-ring 9 engaged with the button loop 8 or belt loop 6, according to which fastening means, that is, the button or belt, is provided. Furthermore, the attachment of the chain in either instance is much neater in appearance and much more secure than in those instances wherein it has been attempted to encircle the suspended end or 110 the belt by a part of the chain itself.

I am aware that chains have heretofore

been made provided at both ends with button loops for attachment to suspender buttons on the waist-bands of trousers for the purpose of suspending the latter; also with 5 hooks and clasps for attachment to the waist-band of trousers, and hence I make no claim to such; but I am not aware that a chain has heretofore been made having at one end a belt loop, and at the opposite end 10 a button loop, with either of which a key-ring may be secured or engaged, and hence:—

What I claim is:—

An article of the character described consisting of a flexible chain provided at one

end with a loop oblong in shape and adapted to encircle a belt, and at the opposite end with a loop adapted to engage with a button, whereby the article may be secured either to a belt or button at one end and 20 carry a key ring at its opposite end.

Signed at New York, borough of Manhattan, in the county of New York and State of New York, this 7th day of June, A. D. 1911.

ROBERT WACHENHEIM.
